UNITED STATES PATENT OFFICE.

HENRY HURLBUT JAMES, OF BUFFALO, NEW YORK.

DESIGN FOR A WATCH OR CLOCK DIAL.

SPECIFICATION forming part of Design No. 27,094, dated May 25, 1897.

Application filed October 31, 1896. Serial No. 610,767. Term of patent 14 years.

To all whom it may concern:

Be it known that I, HENRY HURLBUT JAMES, a citizen of the United States of America, residing at Buffalo, in the county of Erie and State of New York, have invented a certain new and useful Design for Watch and Clock Dials, of which the following is a specification, reference being had to the accompanying drawing.

5 This invention relates to watch and clock dials, and has for its object the ornamentation of such dials to increase their artistic finish and at the same time providing a dial on which the reading of the time will be more readily accomplished.

With these and other objects in view the design consists in certain details which will be hereinafter more fully described, and specifically pointed out in the annexed claim.

10 In describing the design in detail reference is had to the accompanying drawing, forming part of this specification, wherein like numerals of reference denote the same parts.

In the drawing I show a face view of a dial, illustrating the ornamentation.

15 I show the Roman numerals set back from the edge of the dial a considerable distance, and arranged over each of said numerals with their points standing toward the hour-marks are indicators with a wide base tapered to a point, as shown, and the sides of the indicators are curved slightly. Outside of the hour indications are the numerals "5," "10," "15," "20," "25," "30," "35," "40," "45," "50," "55," and "60," this arrangement giving an 30 35 artistic and finished appearance.

Having fully described my design, what I claim is—

20 The design for a watch and clock dial as herein shown and described.

40 In testimony whereof I affix my signature in presence of two witnesses.

HENRY HURLBUT JAMES.
